UNITED STATES PATENT OFFICE

JOSEPH NEEDHAM, OF PASSAIC, NEW JERSEY

ROTARY OVEN

Application filed October 27, 1931. Serial No. 571,347.

This invention relates to what are known as rotary baking ovens; and the object of the invention is to provide an oven of this class made up of a plurality of sections so constructed as to permit the quick assemblage of an oven in making an installation, and also facilitating the packing and shipping of the several parts of the oven; a further object being to provide an oven of the class described involving a simple, strong and durable frame structure with a plurality of wall sections readily assembled in connection with the frame structure in erecting the oven; a further object being to provide a rotary table composed of a plurality of plate sections forming a light and yet strong and durable table; a still further object being to provide means for adjustably supporting the table so as to properly align the same with the 10 peel door of the oven; and with these and other objects in view, the invention consists in an apparatus of the class and for the purpose specified, which is simple in construction, efficient in use, and which is 15 constructed as hereinafter described and claimed.

The invention is fully disclosed in the following specification, of which the accompanying drawings form a part, in which the 20 separate parts of my improvement are designated by suitable reference characters in each of the views, and in which:

Fig. 1 is a transverse, sectional view through an oven made according to my invention, the section being on the line 1—1 of Fig. 3.

Fig. 2 is a sectional plan view on the line 2—2 of Fig. 1 with parts of the construction broken away and in section.

Fig. 3 is a section on the line 3—3 of Fig. 1.

Fig. 4 is an enlarged, sectional detail view of part of the construction shown in Fig. 3; and,

Fig. 5 is a partial section on the line 5—5 of Fig. 3 on an enlarged scale.

Heretofore, in the construction of ovens of the class under consideration, it has been customary to build up the oven on the job by the use of brick masonry, steel and the like, making the installation cost very high

by reason of the requirement of skilled labor. It is the principal feature of my invention to provide an oven of the class under consideration, the several parts of which are constructed in their entirety in a plant or factory and shipped in sections or parts to the job and quickly assembled without the requirement of skilled labor or loss of time. It will also be apparent that by virtue of the construction of my improved oven, the same may be quickly and easily knocked down for shipment or removal whenever desired or necessary.

In the accompanying drawings, I have shown one method of carrying my invention into effect; and in the structure shown, I employ four upright frame members 10, 10a, 10b and 10c which constitute supporting legs in that they extend below the oven proper as clearly seen in Fig. 1 of the drawings. The frame members 10—10a are joined by a top cross frame member 11 and the frame members 10b and 10c are joined by a bottom cross frame member 12. An angle iron ring 13 is coupled with the upper edges of all of the vertical frames 10—10c at the top thereof, and a similar ring 14 joints said frame adjacent the cross frame 12, the latter forming a flange upon which the bottom wall 15 of the oven is supported as well as being supported on the cross frame 12. The top wall 10 of the oven is arranged beneath the ring 13 and is supported in the cross frame 11, and around the periphery of the walls 15 and 16 is the side wall 17 of the oven, which in the construction shown, is of circular cross sectional form. The walls 15, 16 and 17 are all composed of sectional parts, each sectional part consisting of a thin metallic shell within which is a body of insulating material such for example as Rockwool, thus forming a relatively light wall structure for the entire oven. The top and bottom wall sections will be in the form of quarter sections divided along the line of the cross frames 11 and 12, and at ninety degrees to the cross frames as will be apparent on a consideration of the top section 16 as seen in Fig. 2 of the drawings.

The side wall sections 17 are disposed be-

between adjacent walls of the sections 15 and 16 so that the outer surfaces of the sections 17 when assembled, are substantially in alignment with the peripheral walls of the sections 15 and 16, and said sections 17 in the construction shown are made up in eighths so that eight of the sections are required to build the circumferential side wall of the oven, a pair of sections 17 being disposed between each vertical frame. At the adjacent faces of each pair of sections as at 17a, a vertical strip 18 is mounted on the outer surface of said sections to form a reinforcing strip at the intersection at 17a. This strip is secured in position by bolts 19 adjacent the upper and lower ends of the strips 18, the bolts extending between the adjacent faces of the sections 17, the lower bolts also passing through an inner ring 20 at the lower end of the sections 17, and the upper bolts through washers or plates 21 arranged on the inner surface of the sections 17. It is also preferred that the space between the adjacent surfaces of the sections 17 be filled in with an asbestos or other suitable cement as indicated at 22, note Fig. 4 of the drawings. It will also be understood that the adjacent ends of the sections 17 at the vertical frames 10, 10a, 10b and 10c are coupled together by bolts 19a similar to the bolts 19, and the adjacent surfaces are sealed by the asbestos cement 22. It will also be understood that the engaging surfaces between the sections 17 and the top and bottom walls 16 and 15 of the oven will be cemented as indicated at 23, and adjacent surfaces of the separate sections of the top and bottom walls will be cemented together as indicated at 24.

Two of the side wall sections 17 are cut out to form an opening 25 controlling admission to the upper chamber 26 of the oven, in which opening is arranged the usual peel door 27. The opening 25 is lined by a suitable metallic facing 28 which will be preferably cemented in place. Passed through one of the side wall sections 17 are two gas burner tubes 29 for heating the upper chamber 26 of the oven, these tubes being arranged adjacent the peel door 27. Another pair of burner tubes 30 is passed through another section 17, preferably adjacent the opposite side of the peel door and opening into the lower chamber 26a of the oven, said chambers being subdivided by a supporting table 31 and a beveled ring 32 attached to the wall sections 17 and arranged adjacent the peripheral edge of the table, as clearly seen in Fig. 1 of the drawings. At 33 I have shown a flue discharge through which the products of combustion are adapted to pass. This discharge is arranged in the cross frame member 11, but may be positioned and mounted in any desired manner. The table 31 is secured to a shaft 34 arranged centrally and vertically of the oven, the upper end 65 of the shaft projecting through the top wall

16 and having secured thereto a large gear 35 meshing with a pinion 36 on a stub shaft 37. Another gear 38 is secured to the shaft 37 and meshes with a pinion 39 on the shaft of an electric motor 40.

The drive mechanism including the motor and gearing above referred to is supported on the cross member 11 of the frame, the motor 40 and shaft 37 being mounted on a plate 41 secured to the cross member 11. The lower end of the shaft 34 is supported in connection with the cross member 12 so that the weight of the table is primarily taken up by said cross frame, a box-shaped casing 42 being secured centrally of the cross frame 12 and extending therebelow, and an adjustable screw 43 is mounted in connection with the casing and carries at its upper end a thrust bearing 44, upon which the lower end of the shaft 34 rests. With this construction, the shaft 34 including the table 31 attached thereto may be adjusted vertically in the oven to bring the peripheral edge of the table in alignment with the bottom wall of the liner 28 for the opening 25 so as to facilitate the placement of pans upon the table and the removal of the pans therefrom. It will also be noted that the gear 35 is adjustably secured on the upper end of the shaft to compensate for the adjustment of the table 31 by means of a set screw 35a.

The table 31 in the construction shown, consists of two hub portions 45 and 46 secured to the shaft and including intermediate coupling elements 47 whereby a plurality of table forming sections 31a may be coupled together and to the hub portion consisting of the parts 45, 46 and 47 by bolts 48. The coupling elements 47 include side flanges to which the sections 31a are bolted or riveted as seen at 49.

Each section 31a consists of a top plate of such form as to make up one eighth of a complete circular plate, and including side walls, one of which has an outwardly projecting flange 31b arranged adjacent the periphery of the table 31, and the other side wall having a similar flange 31c arranged adjacent the axis of the table. It will therefore be apparent that the separate sections 31a are reinforced and interlocked at their adjacent surfaces, which adjacent surfaces are preferably cemented together to form a smooth top surface. The outer ends of the side walls of each section 31 are cut out and bent to form flanges 31d disposed inwardly of the peripheral edge of the sections, and to which an annular angle iron ring 50 is secured. This ring reinforces the peripheral edges of the sections 31a as well as maintaining said sections in proper horizontal alignment with respect to each other. It will be understood that by coupling the sections 31a to the couplings 47 in the manner described, the same may be readily assembled together and cou-

pled with the hub portions 45 and 46 by the bolts 48.

From the foregoing, it will be apparent that by virtue of my improved oven construction, the complete apparatus may be quickly assembled at the place where the oven is to be erected, and when assembled, the oven will possess all of the desirable characteristics of apparatus of this class, such for example as the heat insulation walls, the rotary table, all of which is of light and yet strong and durable construction, and it will thus be seen that a material saving in the cost of manufacturing the several parts of the apparatus as well as the cost of erecting the same will be effected.

It will also be understood that while I have shown certain type and arrangement of burners in connection with my improved oven, and one method of discharging the products of combustion therefrom, that I am not necessarily limited in this respect, nor am I limited to the direct or substantially direct heating of the products placed on the table for baking, and various other changes in and modifications of the construction herein shown and described may be made within the scope of the appended claims without departing from the spirit of my invention or sacrificing its advantages.

Having fully described my invention, what I claim as new and desire to secure by Letters Patent, is:

1. An oven of the class described comprising a frame consisting of a plurality of vertical frame members, two opposed frame members being coupled by one transverse top frame, two other vertical frame members coupled by a lower cross frame arranged at right angles to the first named cross frame, a rotatable table including a shaft supported upon the bottom cross frame, and means for vertically adjusting said shaft and table with respect to said cross frame.
2. An oven of the class described comprising a frame consisting of a plurality of vertical frame members, two opposed frame members being coupled by one transverse top frame, two other vertical frame members coupled by a lower cross frame arranged at right angles to the first named cross frame, a rotatable table including a shaft supported upon the bottom cross frame, means for vertically adjusting said shaft and table with respect to said cross frame, the upper end of said shaft projecting through the top cross frame, and means supported in connection with the top cross frame for rotating said shaft.
3. An oven of the class described comprising a frame consisting of a plurality of vertical frame members, two opposed frame members being coupled by one transverse top frame, two other vertical frame members coupled by a lower cross frame arranged at
4. A rotary oven of the class described comprising an oven body and a frame for supporting said body, said frame consisting of a plurality of vertical frame members forming supporting legs for the oven, annular frame members coupling and spacing said vertical frame members and arranged at the upper and lower surfaces of the oven body mounted therein, and top and bottom cross frame members engaging the upper and lower surfaces of the oven body, said oven body consisting of top, bottom and side walls, and all of said walls being composed of independent, preformed sections, each section consisting of a comparatively thick wall containing heat resisting material.
5. A rotary oven of the class described comprising an oven body composed of top, bottom and side walls, each constructed from a plurality of independent preformed sections, each section consisting of spaced wall plates with a filler of heat resisting material, a frame for supporting the oven body consisting of vertical frame members spaced about the periphery of the oven body and projecting therebelow to form supporting legs, annular rings coupling said vertical frames together and arranged one at the top and the other at the bottom of the oven body to position said body in the frame and transverse frame members arranged one at the top and the other at the bottom of the oven body, a shaft arranged centrally and vertically of the oven body and supported in said transverse frame members, a table secured to said shaft within the oven body, the shaft projecting at the top of the oven, and means involving an electric motor supported in connection with the top cross frame member for rotating said shaft and table.
6. A rotary oven of the class described comprising an oven body, the top, bottom and side walls of which are composed of independently formed sections and a frame for supporting the oven body consisting of a plurality of vertical frame bars projecting below the oven body to form supporting legs, two annular rings for supporting and positioning the oven body at the upper end of the bars and top and bottom cross frame members arranged upon the top and bottom walls of the oven body, an opening formed in the side wall of the oven body controlling admission to the chamber of said body, a table rotatably

right angles to the first named cross frame, a rotatable table including a shaft supported upon the bottom cross frame, means for vertically adjusting said shaft and table with respect to said cross frame, the upper end of said shaft projecting through the top cross frame, means supported in connection with the top cross frame for rotating said shaft, said last named means comprising an electric motor and a gear chain between said shaft and the shaft of the motor.

- mounted in said chamber, said table including a shaft projecting through the upper and lower walls of the oven body and said cross members, and means supported in connection with the bottom cross frame member for adjusting said shaft and table vertically in the chamber of the oven to position the upper surface of the table with respect to the opening in said oven.
7. A rotary oven of the class described comprising an oven body and a frame for supporting said body, said frame consisting of a plurality of vertical frame members forming supporting legs for the oven, annular frame members coupling and spacing said vertical frame members and arranged at the upper and lower surfaces of the oven body mounted therein and top and bottom cross frame members engaging the upper and lower surfaces of the oven body, said oven body consisting of top, bottom and side walls, all of said walls being composed of independent, preformed sections, each section consisting of a comparatively thick wall containing heat resisting material, the side wall of the oven being composed of eight curved wall sections having adjacent edges arranged in abutting relation and forming a cylindrical oven chamber therewithin and two of the side wall sections being cut out to form an opening to give access to the chamber of the oven and a peel door controlling said opening, and four vertical frame members being employed, said frame members being arranged at alternate intersections of said side wall sections, and vertical finishing strips arranged upon and covering the intermediate intersections of the side wall sections.
8. A knock down oven of the class described comprising a frame consisting of a plurality of vertical frame members, two opposed frame members being coupled by one transverse top frame, the other two vertical frames being coupled by a lower cross frame arranged at right angles to the first named cross frame and vertically spaced annular rings joining all of said frame members, an oven body supported in the frame between and by the top and bottom cross frames and said rings, a vertical shaft supported in the top and bottom cross frames centrally thereof and extending through the oven body, a rotatable table coupled with said shaft within the top and bottom cross frames, means involving an electric motor supported in connection with the top cross frame for rotating said shaft and table, and means in the bottom cross frame for vertically adjusting the shaft and table in the oven body.
9. A knock down oven of the class described comprising a frame consisting of a plurality of vertical frame members, two opposed frame members being coupled by one transverse top frame, the other two vertical frames

being coupled by a lower cross frame arranged at right angles to the first named cross frame and vertically spaced annular rings joining all of said frame members, an oven body supported in the frame between and by the top and bottom cross frames and said rings, a vertical shaft supported in the top and bottom cross frames centrally thereof and extending through the oven body, a rotatable table coupled with said shaft within the oven body, said shaft projecting through the top and bottom cross frames, means involving an electric motor supported in connection with the top cross frame for rotating said shaft and table, means in the bottom cross frame for vertically adjusting the shaft and table in the oven body, said table dividing the oven chamber into top and bottom compartments, and a beveled ring arranged around and adjacent the periphery of the table.

In testimony that I claim the foregoing as my invention I have signed my name this 20th day of October 1931.
